H. R. HUGHES.

METHOD OF AND APPARATUS FOR EARTH BORING.

APPLICATION FILED MAY 21, 1918.

1,283,191.

Patented Oct. 29, 1918.

HOWARD R. HUGHES, Inventor

By His Attorney Jesse R. Stone

UNITED STATES PATENT OFFICE.

HOWARD R. HUGHES, OF HOUSTON, TEXAS.

METHOD OF AND APPARATUS FOR EARTH-BORING.

1,283,191.

Specification of Letters Patent. Patented Oct. 29, 1918.

Application filed May 21, 1918. Serial No. 235,767.

To all whom it may concern:

Be it known that I, HOWARD R. HUGHES, a citizen of the United States, residing at Houston, Harris county, Texas, have invented a certain new and useful Improvement in Methods of and Apparatus for Earth-Boring, of which the following is a full, clear, and exact description, such as will enable others skilled in the art to which

10 it appertains to make and use the same.

My invention relates to a method of and apparatus for earth boring, with particular application to the drilling of horizontal holes with rotary drills. It has for its object the 15 maintaining of the hole in a straight line and also the straightening of a hole already bored which has taken a curved or crooked course.

In the drilling of wells and tunnels or horizontal bores in the earth, the drill will 20 sometimes be directed laterally from the straight course which it is designed to follow and a crooked hole results. This may result from several causes; it may be because of fissures or crevices in the strata or be- 25 cause of inequalities in the density of the material being drilled. An inclined strata of rock will sometimes cause the bit to take a direction inclined from the direction de- sired.

30 The drill stem ordinarily used for this sort of drilling is not sufficiently strong to prevent its being bent as the bit is diverted from its direct line and, as the drill takes a crooked course, the drill stem will bend suffi- 35 ciently to accommodate itself to the crooked hole. I have found that if the guide sleeve is positioned upon the drill stem in the rear of the drill the said drill stem may be sufficiently strengthened and made steady so that the 40 bit may not be easily diverted from its straight course. If the hole does become crooked, the correct positioning of a strengthening or guide sleeve will help to straighten it.

45 With particular reference to the drawing forming a part of this specification and wherein similar characters of reference relate to like parts throughout the several views: Figure 1 is a side view showing an ordinary rotary disk drill operating in a crooked hole. Fig. 2 is a similar view showing the use of my spacing or guide sleeve,

Fig. 3 is a transverse section on the line 3—3 of Fig. 2 and Fig. 4 is a similar section on the line 4—4 of Fig. 2.

55

In the drawing I have shown my method of straightening a crooked hole as applied particularly to a horizontal bore but it is obvious that this method could be applied to a hole bored in any direction and especially to a vertical hole, and I do not wish to limit myself in the use of my method to a hole bored in any particular inclination or direction.

In Fig. 1 I have shown a drill bit 12 of 65 ordinary construction operating in a hole designated in the figure by the numeral 11. The bit is attached to a hollow drill stem 10, and is shown as being bent in the hole by the diversion of the bit from a direct line 70 by inequalities in the material.

The operation of straightening the hole is accomplished by the use of my guide sleeve 16. It has been found by experiment that the use of one or more of these guide sleeves, 75 properly positioned outside the drill stem 10, will so support the drill bit that it will be guided always in a direct line. The exact point at which the guide sleeve should be placed upon the drill stem, in order to 80 accomplish this result, can only be determined by experiment and it is usually found that more than one of the guide sleeves may be necessary to accomplish the result. One sleeve, however, if properly positioned is 85 often sufficient.

The construction of my guide sleeve is thought to be entirely novel. It consists of a cylindrical length of pipe of a size larger than the drill stem 10 and is adapted to fit 90 exactly within the bore 11 drilled by the bit 12. The sleeve 16 is spaced from the drill stem and rigidly held in its proper spaced position outside the drill stem by several spacing blocks 17 of which I have shown 95 four in number. These spacing blocks 17 are attached rigidly to the drill stem 10 and to the sleeve by means of bolts 18, shown in dotted lines in Figs. 5 and 6. After the spacing sleeve has been fixed in place upon the drill stem radial holes 19 are bored 100 through the outer sleeve 16 and the inner pipe 10 as shown at 20 therein. These holes 19 and 20 are bored radially toward the

center of the hollow drill stem at a point midway between each of the spacing blocks as shown in Figs. 5 and 6. The spaces 22 between the blocks 17 are adapted to furnish 5 a backward course for the flushing water used in the drilling operation.

In the operation of a drill, the rotating stem of which is provided with my guide sleeve 16, the sleeve will, as shown, rotate 10 with the drill stem. To prevent the sticking of the sleeve within the hole, streams of the flushing water within the drill stem will be forced laterally through the holes 20 and 15 19 and thus act as a sort of lubricant for the rotating sleeve. As the drill bit is fed forwardly in the drilling operation, earth and other disintegrated matter will be carried 20 backwardly by the flushing water through the channels 22 within the guide 25 sleeve and will thus be carried outwardly toward the surface. It occasionally happens that the force of the returning current is not sufficient to prevent the clogging of the passages 22 and in order that at least 30 one of the passages may be retained always open, a slot 21 is cut longitudinally in one side of the spacing sleeve. This slot is preferably of a length somewhat shorter than the sleeve and stopping just short of 35 each end of said sleeve as shown in Fig. 4. The slot may, however, be the full length of the sleeve if desired. Each lateral lip 23 at the side of the slot is bent inwardly somewhat as shown in Figs. 5 and 6. If it 40 is found that the channels 22 are becoming clogged the drill stem 10 is reciprocated in the bore hole and it is found that any matter clogged within the longitudinal slot 21 will be worked longitudinally by said recip- 45 rocation out of the channels 22 and open up the hole thus again allowing the passage of the flushing water.

This guide sleeve may be used as a means 45 of preventing the drill from deviating from the direct line and also as a means of straightening the hole after the same has become crooked. In using this device to straighten the hole the bit is withdrawn 50 from the well and detached from the drill stem. The spacing sleeve is then fitted over the end of the drill stem to a point somewhat to the rear of the forward end of the stem and is there attached, the spacing blocks being inserted within the sleeve and 55 upon the drill stem. The blocks are retained in place by the fastening bolts. In the sides of the passages, formed between the spacing blocks, radial holes 19 and 20 are then bored for the purpose described. 60 The bit is then again attached to the end of the drill stem and is inserted into the well. The spacing sleeve, being set somewhat to the rear of the bit, will hold the bit in a direct line so that when the bend

in the hole is reached the bit will still be 65 held in a straight line and will bore a straight hole.

The use of this spacing sleeve, or a number of these spacing sleeves, upon the drill stem during the drilling operation will 70 serve to maintain the bit in its correct position and will avoid any lateral deviation due to any inequalities in the material being operated upon.

Having thus described my invention, what 75 I claim as new and desire to protect by Letters Patent, is:

1. In a device of the character described, a drill stem, a guide sleeve thereon, and spacing blocks between said drill stem and 80 said sleeve, said stem and said sleeve having perforations therein.

2. In a device of the character described, a drill stem, a cylindrical guide sleeve spaced outside said stem, spacing blocks 85 forming channels between said sleeve and said stem, and radial perforations in said sleeve and said stem.

3. A guide sleeve for rotary boring drills comprising a short length of casing of a 90 size adapted to fit the hole being drilled, spacing blocks to space the sleeve from the drill stem, and rows of radial perforations in said sleeve.

4. A guide sleeve for rotary boring drills 95 comprising a short length of casing adapted to snugly fit the hole being drilled, and spacing blocks attached interiorly of said sleeve, said sleeve having rows of perforations therein between said blocks.

5. A rotary drill stem, a guide sleeve therefor comprising a sleeve outside said stem, and spacing blocks attached rigidly to said sleeve and to said stem, said stem and said sleeve having registering radial 105 perforations therein for the purpose described.

6. A rotary drill stem, a guide sleeve therefor, comprising a short length of casing adapted to fit closely within the hole 110 being bored, spacing means by which said sleeve is attached to said stem, said stem and said sleeve having perforations therein.

7. A guide sleeve for a rotary drill stem, said sleeve adapted to be spaced outside 115 said stem, said sleeve having longitudinal rows of perforations therein, and a longitudinal slot on one side thereof for the purpose described.

8. A spacing and guide sleeve for rotary 120 boring drills comprising a short length of casing adapted to be spaced outside the drill stem, said sleeve having rows of perforations and a longitudinal slot therein, said slot having inwardly curving lips on both 125 sides thereof for the purpose described.

9. A method of straightening a crooked hole comprising withdrawing and detaching

the drill from the drill stem, placing on said drill stem a means adapted to maintain said stem in a straight line, reattaching the drill to the stem, and when the crooked point is 5 passed, continuing the drilling operation as before.

10. A method of straightening a crooked hole in earth boring, comprising withdraw-

ing and detaching the drill from the drill stem, spacing outside the drill stem a sleeve 10 adapted to maintain the drill in a straight line, again attaching the bit and proceeding with the drilling operation as before.

In testimony whereof, I hereunto affix my signature this the 18 day of May, 1918.

HOWARD R. HUGHES.
